ELEVATOR DOORLOCK

Joseph H. Borden and Charles J. Kett, Philadelphia, Pa., assignors to Atlantic Elevator Company, Inc., Philadelphia, Pa., a corporation of Pennsylvania

Application January 3, 1934, Serial No. 705,084

19 Claims. (Cl. 187—31)

The present invention relates to elevators, and more particularly to the provision of an improved combination door lock and control mechanism for automatic elevators such as are used in small apartment houses, private homes and the like, and thus intended to be operated by the passengers themselves and left unattended when not in use.

In elevators of this type it is customary to provide in the elevator cab a control board or panel carrying suitable operating switches by means of which a passenger may cause the cab to ascend or descend in the hatchway while a push button is provided at each floor level exteriorly of the hatchway by means of which a prospective passenger may cause the cab to move to his floor when it is resting at some other floor level. Moreover, the doors of the hatch at the various floor levels are usually made self closing and so interconnected with the elevator control mechanism as to render its energization impossible when any one of them is open.

Various control and locking mechanisms have heretofore been employed in elevators of this character to prevent them from being operated save when all the hatchway doors are closed and securely locked but, as far as we are aware, none of them has been completely satisfactory for its intended purpose.

It is therefore a principal object of our invention to provide a door lock and associated mechanism which, when installed adjacent each hatchway door of an automatic elevator, is, among other things, effective, first, to positively prevent operation of the main motor or other means for moving the cab in the hatchway unless all the hatchway doors are closed and locked; second, to prevent any door from being opened until the cab has stopped at one of the floors, and, third, to then allow the door at that floor only to be opened and to keep the other doors locked until the cab ultimately comes to rest at another floor.

A further object of our invention is to provide an improved elevator door lock of the class described comprising means, positively actuated by mechanism carried by the cab, effective to release the locking mechanism and permit the adjacent door to be opened after the cab reaches the floor level, simultaneously with the opening of that door, to deenergize the system and prevent operation of the cab until the door is again closed, and, upon subsequent operation of the cab, to lock the door and keep it locked so it cannot be reopened until the cab returns to that floor.

A further object of the invention is to provide a lock of the class described comprising a housing designed to be let into the jamb of the door at each floor and latch mechanism adapted for association with the corresponding door, which housing in the preferred embodiment of the invention contains in addition to a safety switch and the locking mechanism per se, a floor limit switch in combination therewith and actuated by the same means, as well as a push button by which the cab is summoned to the floor, so that a single cable carrying the various conductors for the circuits in which the safety switch floor limit switch and push button are included, may be brought to the housing and all the connections made therein, thus facilitating initial installation and maintenance of subsequent satisfactory operative conditions.

A still further object of the invention is the provision in a lock of the general character of that to which the invention relates, of means for controlling the action of the locking mechanism in accordance with the movements of the cab and insuring a positive and certain actuation thereof to release the lock as the cab reaches the floor and to reengage it after the cab has moved therefrom, said means in their preferred embodiment comprising, among other things, cams carried by the cab cooperative with parts extending to the locking mechanism contained within the housing.

Still other objects, purposes and advantages of the invention will hereinafter appear or will be fully understood from the following description of a preferred embodiment thereof shown in the accompanying drawings.

In its said embodiment, our improved door lock mechanism comprises, generally speaking, a housing let into and secured in the jamb of the door in such position that actuating means, carried by the cab, may engage means carried by the housing to effect operation of the locking mechanism in the latter to thereby release a latch and associated parts carried by the door itself; for convenience of illustration and simplification of description, we have shown in the said drawings but a single lock in association with an elevator cab, hatchway and door construction of a usual type, but it will of course be understood that a similar lock is in practice located at each floor communicating through a door with the hatchway.

In the said drawings, Fig. 1 is a fragmentary view partly in front elevation and partly broken away into vertical section of the lock with the housing cover plate removed, the elevator door and door jamb, with the door locked in closed po-

sition just prior to the ascending cab coming into registry with the floor; Fig. 2 is a vertical section of the lock housing and enclosed parts on the line 2—2 in Fig. 1; Fig. 3 is a side elevation of certain 5 of the parts shown in Fig. 1, particularly designed to illustrate the lock actuating arm and means carried by the elevator cab for effecting its movement; Fig. 4 is a view generally corresponding to Fig. 1 but showing the parts in unlocked position 10 as when the door is about to be opened after the cab has attained proper registry with the floor; Fig. 5 is a vertical section on line 5—5 in Fig. 4, generally corresponding to Fig. 2, while Fig. 6 similarly corresponds to Fig. 3. Fig. 7 is a fragmentary view, partially in plan and partially in 15 horizontal section, of the lock and associated mechanism shown in the preceding figures, and Fig. 8 a fragmentary vertical section corresponding to Fig. 1 except that certain parts are 20 shown in abnormal positions to facilitate explanation of their operation under unusual circumstances. In the several figures, like characters are used to designate the same parts.

We have diagrammatically indicated in the 25 drawings a conventional hatchway H with a front wall W having jambs J, J' on each side of the door D which is hinged to J'; within the hatch the cab C is arranged for vertical movement in response to suitable energization of its actuating 30 mechanism (not shown).

The latch and associated mechanisms generally designated as 1 are, as usual, mounted in and secured to the door D while the housing 2, 2' and 2'' forming the latch keeper and enclosing the 35 locking mechanism is set in the door jamb J and firmly secured therein.

From the housing, which is a box-like metal structure having removable front and back cover plates 2', 2'', an actuating shaft 3 projects in a 40 direction opposite that of the door and supports at its outer end, which terminates in the hatch beyond the jamb J, an actuating arm 4 provided with a cam-engaging roller 5, the roller thus lying in the path of a cam 8, hereafter more particularly 45 described, fixed to the cab C whereby the actuating arm is oscillated through a relatively small arc as the main face of the cam is moved into or out of engagement with the roller as the result of movement of the cab. The cam on the cab and 50 the roller and actuating arm on the shaft are so arranged with respect to their associated parts that when the cab is in substantial registry with the floor the shaft occupies one position of rotative adjustment and when the cab moves out of 55 such registry the shaft is moved to another position of such adjustment.

The shaft 3, when moved from one of said 60 positions to the other by the cam as a result of movement of the cab, causes actuation of certain control mechanisms within the housing, whereby the door is locked or unlocked, and certain of the electrical devices entering into the elevator operation are energized or deenergized, the specific 65 functions being performed in coordinated sequence and in correspondence with the direction in which the shaft is moved by the cam. Thus, in the example shown in the drawings, when the shaft moves in a clockwise direction as from the position shown in Fig. 3 to that shown in Fig. 6, 70 as during movement of the cab to an upper floor from a lower one, the door locking mechanism within the housing is actuated to unlock the door, so that it may readily be opened by an occupant or a prospective occupant of the cab. A limit 75 switch L located in the housing is preferably sub-

stantially simultaneously actuated by the movement of the shaft 3 to stop the cab in proper relation to the floor level, although this switch may, if desired, be located outside the housing and 80 separate and independent limit switch operating mechanism employed for actuating it as several such mechanisms are well known in the art.

In accordance with our invention, however, on 85 release of the door locking mechanism in the manner to which reference has been made, and subsequent retraction of the door latch in opening the door, a safety switch S also included in the housing is opened, and the entire system thereby deenergized, preventing movement of the 90 elevator in response to operation of any of the controlling switches or buttons by means of which it is normally operated when the safety switch is closed. As will hereinafter more fully appear, this switch S is closed only when the door associated with it is also closed, and it is thus evident 95 that operation of the elevator when the door is open is impossible.

In the specific embodiment of our invention shown in the drawings, the shaft 3 is journaled in bosses formed in the walls of the housing and 100 carries a collar 10, secured thereto by a pin 11, having substantially diametrically opposed generally vertically extending arms 12, 13 formed integrally therewith. The end faces of these arms serve, in effect, as cams for actuating other 105 parts in the housing as they are moved in opposite directions by movement of the shaft under the influence of cam 8 on the cab, assisted in the locking direction by a coil spring 14, surrounding the shaft. Thus, the downwardly depending arm 110 12 actuates a spring pressed door latch locking lever 15 which is pivoted at 16 to one wall of the housing and carries at its free end a depending 115 spring pressed pivoted trigger or detent 17 which consequently moves with the arm in a short vertical path adjacent an opening 18 in the housing through which the door latch 19 projects when the door is closed.

The projecting portion of the latch 19 is of 120 arcuate form and is provided on its convex surface with a pair of notches 20, 21 in one of which, normally the notch 20, the trigger is engaged when depressed, i. e., when held in the position shown in Fig. 1 through engagement of the arm 12 with the lever 15. The free end of the latch projects 125 below the notch 21 and engages an insulated finger 23 of the safety switch S when entered sufficiently into the housing to thereby maintain this switch in circuit closing position.

The safety switch S may be of any suitable or 130 desired construction, but we prefer to employ, and have shown, a switch comprising a spring pressed lever 25 pivoted between bosses on the housing and to which the finger 23 is secured, the latter having on its free end a depending post 26 135 upon which a switch plate 27, desirably made of copper, is slidably disposed. The plate is yieldingly urged downwardly toward the lower end of the post by a spring 28, but is prevented from being forced off the end of the post by a pin 30; 140 lost motion of the plate relatively to the pin is thus permitted, so that when the finger is depressed, spaced contacts 31 carried by the plate are brought into satisfactory electrical connection with correspondingly spaced contacts 32 carried by and insulated from the housing without 145 damage to the parts. A circuit between the contacts 32 is thus completed when the finger 23 is depressed by the latch but is broken by the upward movement of the finger when the latch is 150

retracted and, as heretofore indicated, breaking of this circuit through the safety switch deenergizes the entire system, the contacts 32 being in electrical connection therewith through a suitable cable, which may contain additional conductors for other connections, and be led into the housing through a hole 33 in the side of housing 2. It will thus be apparent that normal operation of the elevator is possible only when the safety switch is depressed by the latch to close its circuit.

The limit switch L to which reference has been made, is located above shaft 3 and is preferably of generally similar construction to the safety switch except that its spring 34 urges it toward circuit-closing instead of toward circuit-opening position. It is opened in opposition to the action of this spring by engagement of the end of arm 13 with a lug 35 on its pivoted arm 36 when the shaft 3 is turned counterclockwise by coaction of cam 8 with roller 5 as the cab approaches the floor, and thereby shuts off the actuating current so the cab can drift into proper registry with the floor before coming to rest.

Conversely, when the cab leaves the floor, the shaft 3 is turned in the opposite direction, the limit switch is permitted to close, the locking lever 15 is depressed, and the trigger 17 brought into engagement with the latch, since under normal conditions the elevator cannot leave the floor unless the safety switch S is held in circuit closing position by the latch 19 and the latter is therefore in position to be engaged usually in the notch 20 by the trigger 17.

The arms 12, 13 respectively are provided with stop screws 37, 38 held in position by lock nuts and selectively adapted to engage the front cover plate 2' of the housing 2 to thereby adjustably limit the movement of the arms and hence of the shaft 3 in opposite directions, as clearly indicated in Figs. 2 and 5.

The door latch 19 is actuated from a door knob 40 fixed to a squared shaft 41 which extends thru the latch housing 42 an arm 43 secured to the shaft and a floating link 44 pivoted to both the arm and the latch 19 providing a mechanical leverage whereby rotation of the shaft thru turning the door knob in either direction retracts the latch into its housing. Simultaneously with retraction of the latch a projecting arm 45 integral therewith is brought into engagement with a notched spring pressed trigger 46, pivotally secured at the bottom of the housing and having a toe 48 formed at its free end for engagement with a releasing lug 50. The latter is secured to the door jamb J and projects into the latch housing thru a slot 51 for engagement with the toe 48 when the door is closed. Thus as the latch is retracted in opening the door, the arm 45 is swung downwardly into engagement with the trigger 46, which thereafter holds the latch in retracted position until the door is closed, whereupon the trigger is moved about its pivot by engagement of its toe with the fixed lug 50, thus releasing the arm 45 and permitting the latch to be projected from the latch housing and thru its keeper slot in housing 2 under the influence of a coil spring 53 or other suitable yielding means provided for the purpose.

The main actuating cam 8 mounted on the elevator cab and to which reference has heretofore been made, preferably comprises a vertically extending body 55 desirably formed of wood as that material permits it to readily be made of the proper length and conformation for any par-

ticular job while the elevator is being installed without the necessity for prearranged pattern making, machining and the like. A pair of V-shaped auxiliary cams 56, 57 desirably formed of metal, are disposed adjacent the ends of the body 55, and each is provided with a pair of angular faces 56', 56'', 57', 57'', of which 56', 57'' are substantially parallel to one angular face 55'' of the main cam 8 and to each other, while 56'', 57' are substantially parallel to its other face 55' and to each other. The faces 56', 57' of these cams are respectively spaced from the adjacent faces 55'', 55' of the main cam for a distance slightly greater than the diameter of the roller 5 so that when the latter rides along either of the said faces it will just clear the substantially parallel face of the adjacent auxiliary cam. In the particular embodiment of the invention we have illustrated, the shaft 3 is turned in a clockwise direction to free the locking lever 15 and in a counterclockwise direction to lock that lever, and it will now be apparent that the clockwise movement will be effected by coaction of the cam roll with cam face 55'' when the cab is ascending to the floor and by coaction of said roller with the face 55' when the cab is descending to it thus bringing the roll to the position shown in Fig. 6. When the cab leaves the floor, the counterclockwise movement requisite to lock the lever 15 is positively effected by coaction of the cam face 57' acting on the roll when the cab is moved upwardly and by cam face 56' when the cab moves downwardly, so that in either case the desired certainty of the roll and arm being returned to locking position is positively insured. Thus, under normal conditions, the auxiliary cam faces 56'', 57'' do not coact with the roll but are desirably provided so as to positively return the roll to proper position in case for any reason while the cab is away from the floor it should depart therefrom and assume a position in which it could not be properly contacted by the main cam 8 when the cab returns.

It will now be further apparent that as the shaft 3 is turned to the position shown in Fig. 6 the limit switch is opened by the arm 13 to interrupt the motor circuit and bring the cab to rest at the floor level; that the arm 12 simultaneously moves out of engagement with the locking lever 15 and permits the latter to be raised by the pressure of its actuating spring and that the trigger 17 thus is raised from its engagement in the notch 20. The door may now be released by rotation of the door knob to retract the latch 19 from its keeper whereupon the safety switch S is opened through release of the switch finger by the latch. As the latch is now retracted within the door, when the latter is opened the trigger 46 moves into engagement with the arm 45 on the latch as the toe 47 of the trigger moves away from the lug 50 mounted on the door jamb and the latch is thus held in open position until the trigger is again released through reclosing the door.

When the safety switch is open, it is impossible for the elevator to be moved by either an occupant operating the switches on the panel within the cab or by a prospective passenger at another floor, as it will of course be understood that at each floor similar door locking mechanism is provided as well as a push button 60 operative, when pressed to bring the cab to the corresponding floor from any other one, assuming the entire mechanism and circuits interconnected therewith are in position for such movement, i. e., that all

the doors are closed and the switches in the several door locks are in the position indicated in Fig. 1.

Upon closing of the door preparatory to movement of the cab to another floor, the lug 50 engages the toe 48 of the trigger 46 to release the latch and the latter is projected outwardly from the door and into its keeper in housing 2, its forward end engaging the safety switch to close the main motor circuit and permit normal operation of the elevator. The elevator may then be operated either by means of the controls within the cab or by means of one of the push buttons 60 at another floor in accordance with the usual practice.

Upon movement of the cab in one direction or the other away from the floor one of the faces 56', 57' of the corresponding auxiliary cam, depending on the direction of travel, is brought into engagement with roller 5 as the main cam moves away from it. The roller 5 is thus constrained to substantially follow the adjacent end face of the main cam and the shaft 3 is thereby positively moved in a counterclockwise direction as already explained. This movement of the shaft is assisted to some extent by the spring 14 surrounding the shaft within the housing 2 which also operates to maintain the shaft in locking position after the elevator has moved away. The movement of the shaft, as indicated, results in secure locking of the latch in the keeper, as the locking lever 15 is depressed by the arm 12 upon such movement, and thereby held in depressed position so that the trigger 17 is positively maintained in engagement with latch by pressure of the arm 12 on the locking lever. Under these conditions the shaft cannot be moved in the opposite direction to release the lever 15, and hence the latch except by the main cam 8 so that the cab returns to the floor level to reengage the cam with roller 5 it is impossible for the door to be opened.

Under certain abnormal conditions the elevator may sometimes be moved from the floor level while the door is opened, as by slipping of the cables and/or brakes or for some other reason, with resultant movement of the shaft 3 and lock parts to locking position but with the door latch not entered in the housing 2. If the door is thereafter closed, the latch is projected into the housing as usual and the trigger 17 on the locking arm, being now depressed is engaged by the latch during movement of the latter into the housing and is swung on its pivot as the latch moves under it to the position shown in Fig. 8. Under these conditions, however, the trigger 17 might not seat in the notch 20 because of the retarding effect of its engagement with the latch during movement of the latter although the safety switch might be just closed by the latch, thereby permitting operation of the elevator in a normal way. The auxiliary notch 21 is therefore provided to prevent subsequent opening of the door during the absence of the cab from the floor, since due to the presence of the trigger in the vicinity of the notch 21, an effort to retract the latch through manipulation of the door knob will result in the trigger being seated in that notch while movement of the latch in the opposite direction, i. e., from the position shown in Fig. 8 to that shown in Fig. 1 will seat the trigger in the notch 20 to firmly lock the latch in the housing in the normal way.

Reference has heretofore been made to the specific construction of the safety switch shown

in the drawings comprising a pivoted arm and finger on which is slidably mounted a plate having contacts at its extremities and it will be understood that a switch of this character is desirably used both for the safety switch and for the limit switch, if one is employed in order to permit a certain amount of lost motion between the switch arm and the contacts so that the circuit is not immediately broken upon initial movement of the arms to open the switch, nor are the contacts subjected to possible damage through being forced too severely against the stationary contacts. The specific construction of these switches forms no part of the present invention, however, and if desired, switches of different character may be employed so long as they are capable of performing their intended functions.

It will be apparent from the foregoing that our improved lock is designed for installation in an elevator assembly comprising, among other things, the usual electric circuits by means of which the operation of the cab is effected and controlled, which circuits normally include a safety switch and a floor limit switch respectively generally corresponding in function to our safety switch S and floor limit switch L as well as a push button or like device corresponding to our push button 60 for summoning the cab to any given floor, said switches and button being duplicated at each floor. Since the arrangement of these circuits is well understood, we have therefore herein omitted reference thereto either by way of description or illustration as it is not essential for a proper comprehension of our invention.

It will be further understood that the arrangement of cams for controlling the movement of shaft 3 which we have herein disclosed is particularly suited for installation in an elevator assembly designed to serve but two floors and thus embodying but two of our improved lock mechanisms. When the cab is arranged to serve more than two floors, however, the body 55 of cam 8 will preferably be made of the retiring type instead of fixed so that as the cab passes floors intermediate that from which it started and that at which it is designed to stop, the cam body will not contact the rollers 15 at such intermediate floors, but operate only upon the roller at the floor at which it is desired to stop the car.

In the particular embodiment of the invention herein disclosed, the parts are so arranged that the arm 4 extends angularly upward from the axis of the shaft 3 and is thus turned clockwise to release the locking lever 15 and counterclockwise to lock it, the cam 8 being so constructed that it will effect this clockwise movement of the arm whether the cab is approaching the floor from above or from below, and the auxiliary cams 56, 57 being likewise adapted to positively move the arm in the counterclockwise direction when the cab leaves the floor. However, under some conditions of installation, it may be preferred to so position arm 4 that it will extend angularly downward from the shaft and therefore necessitate its being turned in a counterclockwise direction to release the locking lever 15 and in a clockwise direction to lock it. When such arrangement is desired, it can be readily effected with a locking mechanism of the character illustrated by merely taking out the shaft 3 and reversing the position of the collar 10 thereon and similarly reversing the stop screws 35, 36 so they will contact the cover plate 2' instead of the cover plate 2 when the parts are

reassembled. It will be noted that the sides of locking lever 15 are oppositely inwardly inclined and that the sides of lug 35 of the limit switch finger are also similarly oppositely inwardly inclined so that when the collar 10 is reversed as aforesaid, its arms 12, 13 will coat with these parts in the same way as in the assembly shown in the drawings but, of course, in the opposite direction. It will readily be appreciated that this ability to arrange the parts so that arm 4 can be directed either upwardly or downwardly facilitates installation of the lock under various conditions encountered in practice.

While we have herein described a preferred embodiment of our invention with considerable particularity and with specific reference to its use in automatic elevators, it will be understood that we do not intend to limit or confine ourselves in any way thereto as it may be used with corresponding advantage in elevators of other types, while changes and modifications in the form and arrangement of the various parts of the mechanism will readily occur to those skilled in the art and may be made if desired without departing from the spirit and scope of the invention as defined in the appended claims.

Having thus described our invention, we claim and desire to protect by Letters Patent of the United States.

30. 1. In elevator door locking mechanism, a housing adapted for disposition in the frame of the hatchway door, a retractable latch carried by the door adapted to enter the housing, and means for locking the latch against retraction therewith comprising a latch locking lever pivotally mounted in the housing, a shaft journaled in and extending outwardly from the housing, lever locking means rotatable with the shaft, an arm fixed to the shaft at a point without the housing and extending into the elevator hatchway, and means carried by the cab cooperative with the arm for positively rotating the shaft in opposite directions in correspondence with movements of the cab to thereby move the lever locking means to and from lever locking position.

2. In elevator door locking mechanism, the combination of a housing adapted for disposition in the frame of the hatchway door, a latch carried by the door and movable into the housing, said latch having a notch on the portion which extends into the housing, a latch locking lever pivoted in the housing operable to engage the latch in said notch when in one position and means for moving said lever to said position comprising a shaft journaled in the housing and extending outwardly therefrom, an arm carried by the shaft operative to lock the lever when the shaft is moved to a predetermined position of rotative adjustment and to release it when the shaft is moved to another position of such adjustment, an arm fixed to the shaft without the housing extending into the elevator hatchway cooperative with means carried by the cab to rotate the shaft from one of said positions to the other in correspondence with movements of the cab whereby when the cab is in predetermined relation with the housing, the locking lever is freed from the influence of the locking arm to thereby release the latch, and when the cab is in other positions the locking lever is held in latch locking position.

3. In elevator door locking mechanism, the combination of a housing adapted for disposition in the frame of the hatchway door, a notched latch carried by the door movable into and out of

the housing, and means for preventing withdrawal of the latch from the housing save when the elevator cab is in a predetermined position with relation to the housing comprising a locking lever pivoted in the housing engageable in said notch, yielding means tending to move the lever out of such engagement against the influence thereof and means for releasably maintaining said engagement comprising a shaft journaled in the housing and extending outwardly therefrom into the elevator hatchway, a lever locking arm carried by the shaft contacting the lever when in one position and clearing the lever when in another position, an arm fixed to the shaft outside the housing, means carried by the arm providing a bearing surface and means carried by the elevator cab adapted to engage said surface to positively move the shaft to different positions of rotational adjustment so as to move the lever locking arm into and out of contact with the lever in accordance with movements of the cab.

4. In elevator door locking mechanism, the combination of a housing adapted for disposition in the frame of the hatchway door, a notched latch carried by the door movable into and out of the housing, means for preventing withdrawal of the latch from the housing save when the elevator cab is in a predetermined position with relation to the housing comprising a locking lever pivoted in the housing engageable in said notch, yielding means tending to move the lever out of such engagement against the influence thereof and means for releasably maintaining said engagement comprising a shaft journaled in the housing and extending outwardly therefrom into the elevator hatchway, a lever locking arm carried by the shaft contacting the lever when in one position and clearing the lever when in another position, an arm fixed to the shaft outside the housing, means carried by the arm providing a bearing surface and means carried by the elevator cab adapted to engage said surface to positively move the shaft to different positions of rotational adjustment so as to move the lever locking arm into and out of contact with the lever in accordance with movements of the cab, a switch disposed within the housing having a movable contact finger extending into the path of the latch whereby when the latch is in latching position said switch is closed, and yielding means for moving the finger to open the switch when said latch is retracted from latching position.

5. In elevator door locking mechanism, the combination of a housing adapted for disposition in the frame of the hatchway door, a notched latch carried by the door movable into and out of the housing, means for preventing withdrawal of the latch from the housing save when the elevator cab is in a predetermined position with relation to the housing comprising a locking lever pivoted in the housing engageable in said notch, yielding means tending to move the lever out of such engagement against the influence thereof and means for releasably maintaining said engagement comprising a shaft journaled in the housing and extending outwardly therefrom into the elevator hatchway, a lever locking arm carried by the shaft contacting the lever when in one position and clearing the lever when in another position, an arm fixed to the shaft outside the housing, means carried by the arm providing a bearing surface and means carried by the elevator cab adapted to engage said surface to positively move the shaft to different positions of rotational adjustment so as to move the lever lock-

ing arm into and out of contact with the lever in accordance with movements of the cab, and a pair of switches disposed in the housing, one having a movable contact finger extending into the 5 path of the latch when it is projected into latching position whereby said switch is closed as said latch is so projected and kept closed while the latch is thereafter locked through the medium of said locking lever and yielding means for opening 10 said switch when the latch is retracted after release of said locking means through actuation of said shaft, said other switch having a movable contact finger and yielding means tending to urge it to a closed position, and means carried by the 15 shaft for opening said last mentioned switch against the urge of said yielding means when the shaft is rotated to bring the locking means into locking position.

6. In an elevator door locking assembly, a movable door latch carried by the hatchway door, a 20 housing carried by the door frame adapted to receive the latch to latch the door, the latch having a pair of notches in that portion thereof which extends into the housing, and means for releasably locking the latch against retraction from the 25 housing comprising a locking lever pivoted therein having a movable trigger at its extremity adapted for reception in either of said notches, yielding means tending to move the trigger toward the latch, a shaft journaled in the housing extending into the elevator hatchway, a locking arm carried by said shaft operative to hold the lever stationary after the trigger is disposed in either notch when the shaft is in one position of 30 the latch, a shaft journaled in the housing extending into the elevator hatchway, a locking arm carried by said shaft operative to hold the lever stationary after the trigger is disposed in either notch when the shaft is in one position of 35 rotative adjustment, and to release said lever when the shaft is in another position of such adjustment, an arm carried by the shaft outside the housing, means carried by this arm providing a bearing surface and means carried by the elevator 40 cab cooperative with said surface to move the shaft from one of said positions to the other in correspondence with movements of the cab whereby when the shaft is in one of said positions, the trigger is held in latch locking relation with one or the other of the notches and when in the other of said positions the trigger is 45 released from such relation to allow the latch to be retracted from the housing.

7. In an elevator door locking assembly, a movable door latch carried by the hatchway door, a housing carried by the door frame adapted to receive the latch to latch the door, the latch having a pair of notches in that portion thereof which extends into the housing, and means for 50 releasably locking the latch against retraction from the housing comprising a locking lever pivoted therein having a movable trigger at its extremity adapted for reception in either of said notches, yielding means tending to move the trigger toward the latch, a shaft journaled in the housing extending into the elevator hatchway, a locking arm carried by said shaft operative to hold the lever stationary after the trigger is disposed in either notch when the shaft is in one 55 position of rotative adjustment, and to release said lever when the shaft is in another position of such adjustment, an arm carried by the shaft outside the housing, means carried by this arm providing a bearing surface, means carried by the elevator cab cooperative with said surface to move the shaft from one of said positions to the other in correspondence with movements of the cab whereby when the shaft is in one of said 60 positions the trigger is held in latch locking relation with one or the other of the notches and when in the other of said positions the trigger is released from such relation to allow the latch to be retracted from the housing.

in the other of the said positions the trigger is released from such relation to allow the latch to be retracted from the housing, a switch disposed within the housing below the locking lever having a movable contact finger extending into the path of the latch and yielding means tending to urge the switch to open position, said finger being forced to closed position by the latch when the trigger is disposed in either of the notches and moved to open position by the yielding means when the trigger is released and the latch is retracted from the housing. 80

8. In an elevator door locking assembly, a movable door latch carried by the hatchway door, a housing carried by the door frame adapted to receive the latch to latch the door, the latch having a pair of notches in that portion thereof which extends into the housing, and means for releasably locking the latch against retraction from the housing comprising a locking lever pivoted therein having a movable trigger at its extremity adapted for reception in either of said notches, yielding means tending to move the trigger toward the latch, a shaft journaled in the housing extending into the elevator hatchway, a locking arm carried by said shaft operative to hold the lever stationary after the trigger is disposed in either notch when the shaft is in one position of rotative adjustment, and to release said lever when the shaft is in another position of such adjustment, an arm carried by the shaft outside the housing, means carried by this arm providing a bearing surface, means carried by the elevator cab cooperative with said surface to move the shaft from one of said positions to the other in correspondence with movements of the cab whereby when the shaft is in one of said positions the trigger is held in latch locking relation with one or the other of the notches and when in the other of said positions the trigger is released from such relation to allow the latch to be retracted from the housing, a switch disposed within the housing below the locking lever having a movable contact finger extending into the path of the latch, yielding means tending to urge the switch to open position, said finger being forced to closed position by the latch when the trigger is disposed in either of the notches and moved to open position by the yielding means when the trigger is released and the latch is retracted from the housing. 95

9. In an elevator assembly comprising a hatchway having a door, a cab movable in the hatchway, a latch carried by the door, a housing carried by the door frame, the latch being movable into and out of the housing to latch and unlatch the door, means for positively locking the latch when fully entered in the housing comprising a latch locking lever pivoted within the housing, a shaft journaled in the housing and extending into the hatchway, an arm carried by the shaft operative to move the lever into locking relation with the latch when the shaft is moved to one position of rotative adjustment and to release the lever therefrom when the shaft is moved to another such position, an actuating arm on the shaft exteriorly of the housing extending into the hatchway, a roller on the actuating arm, 100

- 5 a cam carried by the cab adapted to contact the roller to move the shaft from locking to releasing position as the cab approaches the floor, and another cam carried by the cab adapted to contact the roller to positively move the shaft to locking position when the cab departs from the floor.

10 10. In an elevator assembly comprising a hatchway having a door, a cab movable in the hatchway, locking means for the door comprising a movable latch carried by the door, a housing carried by the door frame having an opening adapted to receive the latch, and means for releasably holding the latch in said opening comprising a locking lever pivoted in the housing adapted to engage the latch, a shaft journaled in the housing extending outwardly therefrom, an arm carried by the shaft cooperative with said lever to hold it in latch locking position when the shaft is in one position of rotative adjustment and release it therefrom when the shaft is in another such position, an actuating arm extending into the hatchway from the shaft, a roller on the actuating arm, a pair of opposed cams carried by the elevator cab, one of said cams being adapted to contact the roller and move the shaft to release the first mentioned arm from the locking lever as the cab approaches the floor and the other cam being adapted to contact the roller and positively move the shaft and said first mentioned arm to lever locking position when the cab leaves the floor and yielding means for moving the lever out of locking position when it is relieved from the influence of said first mentioned arm.

15 11. In an elevator assembly comprising a hatchway having a door, a cab movable in the hatchway, locking means for the door comprising a movable latch carried by the door, a housing carried by the door frame having an opening adapted to receive the latch, and means for releasably holding the latch in said opening comprising a locking lever pivoted in the housing adapted to engage the latch, a shaft journaled in the housing extending outwardly therefrom, an arm carried by the shaft cooperative with said lever to hold it in latch locking position when the shaft is in one position of rotative adjustment and release it therefrom when the shaft is in another such position, an actuating arm extending into the hatchway from the shaft, a roller on the actuating arm, a pair of opposed cams carried by the elevator cab, one of said cams being adapted to contact the roller and move the shaft to release the first mentioned arm from the locking lever as the cab approaches the floor and the other cam being adapted to contact the roller and positively move the shaft and said first mentioned arm to lever locking position when the cab leaves the floor and yielding means for moving the lever out of locking position when it is relieved from the influence of said first mentioned arm, said lever comprising a movable trigger and said latch having a pair of notches adapted for its reception.

20 12. In an elevator assembly comprising a hatchway having a door, a cab movable in the hatchway, a housing carried by the door frame, a latch carried by the door and partially movable into and out of the housing, the part of the latch which enters the housing having a pair of notches, locking means for releasably holding the latch in the housing comprising a locking lever pivoted therein, a trigger on the free end of the lever adapted to selectively enter either of the notches, a shaft journaled in and extending outwardly from the housing, an arm carried by the

25 30 35 40 45 50 55 60 65 70 75 80 85 90 95 100 105 110 115 120 125 130 135 140 145 150

shaft operative when in one position to hold the lever against upward movement, yielding means tending to continually urge the lever upwardly to thereby retract the trigger from the particular notch in which it is entered, an actuating arm extending from the shaft into the hatchway, a roller on the actuating arm, and a pair of cams carried by the cab, one of said cams being adapted through coaction with the roller to rotate the shaft in one direction as the cab approaches the floor to release the locking arm from the locking lever, and the other of said cams being adapted through coaction with the roller to positively rotate the shaft in the other direction as the cab leaves the floor and thereby engage the locking arm with the locking lever and positively hold said trigger in one of the notches to prevent retraction of the latch from the housing.

13. In an elevator assembly comprising a hatchway having a door, a cab movable in the hatchway, a housing carried by the door frame, a latch carried by the door and partially movable into and out of the housing, the part of the latch which enters the housing having a pair of notches, locking means for releasably holding the latch in the housing comprising a locking lever pivoted therein, a trigger on the free end of the lever adapted to selectively enter either of the notches, a shaft journaled in and extending outwardly from the housing, an arm carried by the shaft operative when in one position to hold the lever against upward movement, yielding means tending to continually urge the lever upwardly to thereby retract the trigger from the particular notch in which it is entered, an actuating arm extending from the shaft into the hatchway, a roller on the actuating arm, and a pair of cams carried by the cab, one of said cams being adapted through coaction with the roller to rotate the shaft in one direction as the cab approaches the floor to release the locking arm from the locking lever, and the other of said cams being adapted through coaction with the roller to positively rotate the shaft in the other direction as the cab leaves the floor and thereby engage the locking arm with the locking lever and positively hold said trigger in one of the notches to prevent retraction of the latch from the housing.

14. In an elevator assembly comprising a hatchway having a door, a cab movable in the hatchway, a housing carried by the door frame, a latch carried by the door and partially movable into and out of the housing, the part of the latch which enters the housing having a pair of notches, locking means for releasably holding the latch in the housing comprising a locking lever pivoted therein, a trigger on the free end of the lever adapted to selectively enter either of the notches, a shaft journaled in and extending outwardly from the housing, an arm carried by the shaft operative when in one position to hold the lever against upward movement, yielding means tending to continually urge the lever upwardly to thereby retract the trigger from the particular notch in which it is entered, an actuating arm extending from the shaft into the hatchway, a roller on the actuating arm, and a pair of cams carried by the cab, one of said cams being adapted through coaction with the roller to rotate the shaft in one direction as the cab approaches the floor to release the locking arm from the locking lever, and the other of said cams being adapted through coaction with the roller to positively rotate the shaft in the other direction as the cab leaves the floor and thereby engage the locking arm with the locking lever and positively hold said trigger in one of the notches to prevent retraction of the latch from the housing.

- action with the roller to rotate the shaft in one direction as the cab approaches the floor to release the locking arm from the locking lever, and the other of said cams being adapted through coaction with the roller to positively rotate the shaft in the other direction as the cab leaves the floor and thereby engage the locking arm with the locking lever and positively hold said trigger in one of the notches to prevent retraction of the latch from the housing, a switch disposed within the housing beneath the locking lever having a movable contact making finger extending into the path of the latch whereby said finger is moved to closing position as the latch is moved to latching position, yielding means tending to move the finger from closing position when the latch is retracted, a second switch disposed in the housing above the locking lever comprising a movable finger and yielding means operative to urge it to switch closing position, and means carried by the shaft cooperative with said finger to positively move it to switch opening position as the lever locking arm is moved into engagement with the locking lever.
15. In combination with an elevator assembly comprising a hatch having a doorway, a cab movable in the hatch and a door in the doorway, a housing disposed in the frame of the doorway, a latch carried by the door adapted to enter the housing when the door is closed, spring pressed pivoted latch locking means in the housing adapted to engage the latch, a shaft rotatable in the housing, means carried by the shaft adapted to move said locking means to latch engaging position when the shaft is moved to one position, interengageable means respectively carried by the cab and shaft operative to effect rotative movement of the shaft to and from said position when the cab is moved in the hatch and a switch actuated by the latch to complete a circuit when the latch is moved to a position for engagement by the locking means.
16. In elevator door locking mechanism, a notched latch, a housing adapted to receive the latch, a switch disposed in the housing for actuation by the latch, spring pressed means operable to enter a notch in the latch when entered in the housing, locking means operable to move said last mentioned means into notch entering position against the spring pressure, cams providing a plurality of angularly disposed cam faces carried by the elevator cab, and means interengaged with the locking means engageable by the cams to effect movement of the locking means in opposite directions.
17. Elevator safety switch and door locking mechanism comprising a housing having an opening, a safety switch disposed therein adjacent the opening, a latch adapted to enter the opening and actuate the switch, latch locking means disposed in the housing adapted to engage the latch and means for positively actuating said locking means in one direction and for yieldingly actuating said means in the opposite direction in correspondence with movements of the elevator cab.
18. Elevator safety switch and door locking mechanism comprising a housing having an opening, a safety switch disposed therein adjacent the opening, a latch adapted to enter the opening and actuate the switch, latch locking means disposed in the housing movable into engagement with the latch, yielding means for moving said locking means in one direction and means for positively moving said locking means in the opposite direction in correspondence with movements of the elevator cab, said means comprising a rotatable shaft, means carried thereby providing bearing surfaces one of which is adapted to engage and move the locking means, and means carried by the cab adapted to engage the other bearing surface to positively rotate the shaft in opposite directions.
19. In elevator door locking mechanism, a housing, a latch adapted to enter the housing, a locking lever disposed in the housing adapted to engage the latch when entered therein and lock it in the housing, a shaft journaled in the housing, a locking arm carried by the shaft adapted to move the locking lever to effect engagement thereof with the latch, actuating means for the shaft extending into the elevator hatchway, and a cam carried by the elevator cab operative to engage said actuating means substantially concurrently with the initial movement of the cab from the floor level to rotate the shaft and thereby actuate the locking arm to move the locking lever into engagement with the latch.
